W. K. BONHAM.
DOME COVER FOR OIL CARS.
APPLICATION FILED FEB. 25, 1920.

1,398,832.

Patented Nov. 29, 1921.

UNITED STATES PATENT OFFICE.

WILLIAM K. BONHAM, OF COFFEYVILLE, KANSAS.

DOOME-COVER FOR OIL-CARS.

1,398,832.

Specification of Letters Patent. Patented Nov. 29, 1921.

Application filed February 25, 1920. Serial No. 361,198.

To all whom it may concern:

Be it known that I, WILLIAM K. BONHAM, a citizen of the United States, residing at Coffeyville, in the county of Montgomery and State of Kansas, have invented certain new and useful Improvements in Dome-Covers for Oil-Cars; and I do hereby declare the following to be a full, clear, and exact description of the invention, such as will enable others skilled in the art to which it appertains to make and use the same.

The object of the invention is to provide a cover for the dome of a tank car suitable and designed for the transportation of oil and like material of a more or less volatile nature, which, while capable of application and removal with said facility, will prevent the escape of gas or vapor from the dome and hence will minimize or eliminate the risk of fire and explosion to which the transportation of such products under ordinary condition is subject; and with this object in view the invention consists in a construction and combination of parts of which a preferred embodiment is shown in the accompanying drawing, wherein:

Figure 1 is a sectional view of a tank car dome provided with a cover constructed in accordance with the invention.

Fig. 2 is a plan view of the same.

Fig. 3 is a detail view of the latch mechanism showing the retainer in its disengaged position.

The cap or cover consists essentially of a cylindrical body portion or plug 10 which is exteriorly threaded to engage corresponding threads in a seat 11 formed by a collar which is disposed within the dome 12 of the tank car indicated at 13, in registration with the cap or cover opening, and at its inner end said body portion or plug is tapered as indicated at 14 for contact with an inclined or conical seat 15 arranged at the inner terminal of the collar forming the plug seat and constituting in effect a contraction of said plug seat and a stop to limit the inward adjustment of the plug. This contracted portion of the plug seat, formed by the annular conical lid 15 is preferably of brass or equivalent relatively soft metal as also preferably is the tapered portion 14 of the body or plug of the cap or cover to the end that when the latter is screwed snugly to place there is established an intimate tapered tight contact between the plug and the ledge. The body portion of the cap

or cover is preferably flanged as shown at 16 to overlap the wall of the seat and as indicated it may carry a central stud or handle 17 and an eccentric stud 18 with which may be engaged a lever to assist in turning the cap or cover into place or removing the same. Said central and eccentric studs will constitute convenient fulcrums for the lever.

To provide against the possibility of the loosening of the cap or cover by reason of a vibration or jarring of the car in transit the upper surface thereof may be provided with a plurality of sockets 19 for engagement by a latch 20 which may as shown be pivoted as at 21 to a suitable standard 22 or its equivalent rising from the upper end of the dome of the car, and a gravitational weighted locking arm 23 also pivoted upon said standard may be arranged to drop into contact with the latch when the latter is engaged with the adjacent socket 19, to prevent accidental disengagement while permitting the operator when necessary to release the latch merely by lifting the weighted end of the retainer. In the construction illustrated the latter consists of a U-shaped loop of which the closed end is provided with an enlargement 24 disposed transversely to the latch and serving as a weight to bear upon and secure the latch in its cover or cap locking position.

The retainer may be employed to hold the latch in its raised or disengaged position during the time that the cap or cover is unseated or is being removed or replaced to avoid the possibility of injuring the same and to hold it out of the way of the operator, it being simply necessary to raise the latch and drop the retainer over the free end thereof to effect the indicated object. When the latch is required for further use in locking the cap or cover it may be released by raising the retainer whereupon the dropping of the latter will permit it to resume its locking position with relation to the latch to maintain it in engagement with the socket of the cap or cover.

In order that the accumulation of gas or vapor due to evaporation and which may have created a considerable pressure, may be relieved before the cap is entirely removed, the side wall of the cap is provided with one or more vent channels 25 constructed as grooves in the outer surface of the wall and having outlets 26 formed in the rim of the cap exteriorly of the dome, said channels be-

ing closed at their inner ends, when the cap or cover is in its normal or closing position, by the seating of the tapered inner portion 14 of the plug or body of the cap upon the 5 ledge 15. As soon as the cap or cover is turned slightly however to unseat the tapered portion 14 and removed from contact with the bearing ledge 15, the lower ends of said 10 vent channels are exposed, and the pressure of vapor within the dome may escape prior to the complete removal of the cap or cover.

What is claimed is:

1. A tank car provided with a dome having an opening in its top, an internally 15 threaded collar within the dome in line with the opening thereof and terminating at its lower end in a conical seat, and a plug externally threaded to match the internal threads of the collar and having its end tapered to engage the conical seat of the said 20 collar, and having an outer rim to overlap the top of the dome, said rim having lateral

openings therein, and the body of the plug having grooves in its sides in communication at their upper ends with the lateral 25 openings and adapted to be closed at their inner ends by the said conical seat.

2. A tank car provided with a dome and standards, a plug closing the dome and having screwthreaded connection therewith and 30 provided in its top with a plurality of sockets, gravitational latches pivoted to the standards and adapted to engage certain sockets to secure the plug against loosening, and retainers mounted on the standards and adapted 35 to engage the latches to hold them in operative engagement with the plug or out of the path thereof.

In testimony whereof I affix my signature in presence of two witnesses.

WILLIAM K. BONHAM.

Witnesses:

H. B. CHASE,
CAROLYN BURGHART.
